METHOD OF DETERMINING VANADIUM
Daniel J. Brogan, 1649 N. 59th St., Philadelphia, Pa.
Filed Nov. 8, 1961, Ser. No. 151,003
5 3 Claims. (Cl. 23—230)

The present invention relates to methods of performing chemical analyses for vanadium present in combustible materials such as petroleum oils, fuel oil, organic materials, metallo-organic materials and the like.

A purpose of the invention is to greatly reduce the time and reduce the cost of determining vanadium in combustible materials.

A further purpose is to eliminate the danger from sulphuric acid in making vanadium analyses of combustible materials.

A further purpose is to avoid the necessity of running a pilot determination on the test material to establish the ASTM recommended sample size in analyzing for vanadium.

A further purpose is to expedite the programming for injection of additives to protect against vanadium in combustion equipment such as boilers, superheaters, re-heaters and the like.

Further purposes appear in the specification and in 25 the claims.

The drawing illustrates the results of the tests employing the procedure of the invention and the comparison with the ASTM method.

The figure is a series of curves showing vanadium content by the ASTM method in parts per million plotted against sample size in grams and showing test results according to the present invention for reference purposes.

Describing in illustration but not in limitation and referring to the drawings:

Fuel oils are being used for combustion purposes to produce electrical energy and steam for heating which contain substantial quantities of vanadium which cannot be economically removed and which oils are attractively low in price. South American crude oil, such as residual from Venezuela, is an example. The vanadium is particularly harmful to boiler, superheater and reheater tubes since at the operating temperature it forms a liquid complex which is extremely corrosive to the metal of the tubes.

To prevent this corrosive attack, normal practice requires injecting a dry powder additive such as magnesium hydroxide into the combustion chamber to raise the melting point of the vanadium-containing complex so that it will not form a liquid at operating temperatures and will not be corrosive on the heat transfer tubes. The optimum rate of feed of additives depends on the vanadium content of the fuel oil, and the vanadium content varies widely with different oil samples. Accordingly, it is necessary to determine the vanadium content periodically to control the feed of additive in order to obtain proper corrosion protection. Where the quantity of additive is not properly regulated and proves to be excessive, difficulty in heat transfer may result because of a deposit of additive on heat transfer surfaces.

The standard method for determining vanadium in fuel oils is that set forth in ASTM tentative specification D1548-59T, Vanadium in Navy Special Fuel Oil. This method requires of the order of 8 to 15 hours for each analysis, depending upon the size of the sample.

One of the problems presented by the ASTM method is the determination of the sample size, since the recommended sample size varies with the vanadium concentration in the sample. In dealing with a completely unknown sample, it is therefore necessary to make a pilot determination of the approximate vanadium content of

2

the sample in order to determine the recommended sample size to be used in the final determination. As explained later, if the sample size is larger than the recommended sample size, the results obtained by the ASTM method are likely to be appreciably low.

According to the ASTM method, the sample size equals F/C where F is a sample factor depending upon the length of the light path through the solution and the dilution, and C is the expected vanadium concentration 10 in p.p.m. Thus for a given size of absorption cell and a given dilution, the sample size decreases as the vanadium content in p.p.m. increases.

According to the ASTM method, concentrated sulphuric acid is added to a small sample of fuel oil and 15 the mixture is heated while stirring, until a sludge is formed and the sulphur oxides are driven off. This process involves some danger to the operator, and he must proceed very carefully and protect against burns of the skin and particularly the eyes. This step is eliminated 20 in my method.

The residue is heated until it forms a dry coke.

This coke is then reduced to an inorganic ash in a muffle furnace held at a temperature not in excess of 550° C. This process must be performed slowly and carefully as it is essential to oxidize and drive off all carbonaceous material without volatilizing any of the vanadium itself. Care must be used "so that too great an air flow into the muffle will not cause the ash to be blown from the beaker or to be lost because of too rapid burning of the carbonaceous material. Particular care should be taken to avoid contamination of the sample with particles from the roof, walls, and door of the furnace."

The ash is allowed to cool and then is treated with 35 concentrated nitric and sulphuric acids and then heated carefully on a hot plate until most of the nitric acid fumes are driven off. The purpose of the nitric acid is to oxidize the vanadium completely. The purpose of the sulphuric acid is to keep the solution acid and act 40 as an indicator to determine when most of the nitric acid fumes have been driven off, by the initial appearance of the white fumes of sulphur trioxide.

The final product is allowed to cool, carefully neutralized with sodium hydroxide, and sulphuric acid, phosphoric acid and sodium tungstate are added to produce a phosphotungstovanadic acid complex. The recommended concentration of sodium hydroxide is 50% by weight, and this procedure of neutralization involves danger of 45 spattering, possible injury to the operator and possible loss of a portion of the sample. The intensity of the color is then measured in an absorption cell measuring either the absorbance or transmittance at 436 μ or some other suitable wave length.

I have discovered that the speed and cost of the 55 analysis can be greatly improved if both the combustion of the sample and also the oxidation of the vanadium are conducted in a combustion bomb. Combustion bombs are used in other types of analyses and give reliable results, for example, in the analysis of sulphur in coal, in which the sulphur content may be of the order of 300 times as great as the vanadium content in oil and therefore relatively easy to determine.

One of the great advantages of the process of the invention is that the same sample size can be used and 65 will give substantially accurate determinations of vanadium notwithstanding variation in the vanadium content. It is therefore possible to determine vanadium with high accuracy without making a pilot run to determine the recommended sample size.

In accordance with the invention, a suitable weighed 70 sample of combustible material containing vanadium, for

example fuel oil, is placed in a capsule which in turn is placed in the holder of a combustion bomb. A conventional bomb calorimeter may be used of the type which determines the calorific value of coal. The bomb may be used with or without a liner. The liner may be of any suitable material which will not interfere with the test such as glass. Where no liner is employed, the bomb may suitably be made of a temperature and oxygen resistant metal such as nickel or illium (see Metals Handbook, 1961, pages 1117, 1127 to 1129), which will not interfere with the test.

It is preferable to add a small quantity of water to the bomb before the reaction, to dissolve the vanadium oxide formed during the reaction, and aid in removing the vanadium from the bomb.

Oxygen is admitted to the bomb until a suitable super-atmospheric pressure of say 30 atmospheres is reached. It is preferable to provide for cooling the bomb as for example by placing the bomb in a water bath. This can conveniently be done by using a calorimeter housing. The sample is then ignited electrically using the usual bomb igniter. The sample burns in the enriched oxygen atmosphere and the combustion of the sample is completed within about 5 minutes. All of the vanadium present is oxidized to the highest valence.

After the reaction or preferably during the reaction, the bomb is cooled as just described. An additional 5 minute period is allowed after completion of reaction to permit the combustion products to settle within the bomb. The excess of oxygen is then discharged and the bomb is opened. All interior surfaces of the bomb are rinsed with distilled water and the washings are collected. If the washings exceed approximately 30 ml. they are evaporated down to approximately 30 ml.

The procedure for color development and determination is then carried out according to the ASTM method in the usual manner.

Because of the possibility that some small error will occur as a result of reactants, pick-up from the bomb and effect a fuse wire, it is desirable to run a blank to obtain a correction factor for the bomb. This correction factor (scale reading on colorimeter) can be deducted from the vanadium sample readings. If a liner of glass or other suitable inert material is used in the bomb, it will minimize this error. It will of course be evident that as long as the same composition of reactants, the same bomb and the same composition of fuse wire are employed, it will not be necessary to repeat the blank.

The entire analysis can be completed in a time of the order of one hour compared with about 8 to 15 hours for the ASTM method, dependent upon the size of sample used.

It has been found that the method of the invention gives vanadium concentrations which are substantially of the same accuracy as in the ASTM method, and the deviations from the mean of the method of the present invention and of the ASTM method are approximately the same.

Thus, the method of the invention offers the advantage of great saving in time, reduction in expense and avoidance of pilot determinations. Since time is saved, it is possible to obtain tighter control and have less time lag in additions of additive to protect against corrosion from the vanadium.

EXAMPLE I

Take an 0.8 to 1 gram sample of fuel oil and place in a silica or metal capsule in the holder of a conventional combustion bomb or reaction vessel of 350 ml. volume which is suitably clean and ready for use. Introduce 10 ml. of distilled water in the bottom of the bomb. Introduce oxygen under pressure until a pressure of 30 atmospheres is reached.

It is of course understood that the size of sample, the

pressure of oxygen, the volume of water and other similar features may be varied as the capacity of the bomb or other reaction vessel is increased or decreased. The specific values mentioned are intended as guides.

5 The bomb or reaction vessel is placed in a water bath. The sample is ignited by an electrical igniter. At the end of 10 minutes remove the bomb from the water bath, open the valve and remove the excess oxygen slowly. Open the bomb.

10 Wash all interior surfaces of the bomb with distilled water and collect the washings, keeping the total of the washings, if convenient, to a volume below 30 ml. If the volume is in excess of 30 ml., evaporate to conform the sample to a volume of 30 ml.

15 Add to the washings 2 ml. of H_2SO_4 (1:1), 5 ml. of H_3PO_4 (1:2) and 2.5 ml. of Na_2WO_4 solution. The sodium tungstate solution contains 185 grams sodium tungstate, $Na_2WO_4 \cdot 2H_2O$ per liter. Heat the solution to near boiling, cool to room temperature and quantitatively transfer into a 50 ml. volumetric flask, and dilute to a volume of 50 ml.

20 A portion of this phosphotungstovanadic acid complex solution is transferred into an absorption cell and absorbance or transmittance of the colored solution is measured against the reagent blank at 436 mu. A calibration curve is used in converting to quantities of vanadium as explained in the ASTM specification. Good results can also be obtained at 420 mu if a suitable calibration curve is used.

25 It will be evident that variations in the quantities and also in the concentrations used are permissible and the values stated are recommended values which conform to ASTM practice, but may be varied.

COMPARISON OF ASTM METHOD WITH THE BOMB METHOD OF THE PRESENT INVENTION

30 In the ASTM procedure, different sample sizes are recommended for different concentrations of vanadium, and in analyzing a sample on which no data is available, it is necessary to run a pilot analysis to determine the proper sample size to use in the ASTM analysis.

35 The drawing plots average p.p.m. of vanadium as ordinate against average weight of sample in grams for three different lots of oil. Each point plotted on the curves represents the average of 10 determinations. Curve 20 at the top shows a point 21 illustrating the average vanadium determination by the ASTM method using the ASTM recommended sample size, while points 22 and 23 illustrate that the ASTM method gives substantially lower vanadium values if samples larger than the ASTM recommended size are used. The line 24 indicates the ASTM recommended sample size. Point 25 illustrates the average value obtained for vanadium by the bomb technique of the present invention, applied to the same sample of oil and corrected for the blank.

40 Considering now curve 26 for an oil having a lower vanadium content, in this case the recommended ASTM sample size is 27 and the actual sample tested according to ASTM practice gave vanadium values 28 which are almost the same as the value shown at 30 for the bomb technique of the present invention corrected for the blank.

45 Again, when according to the ASTM method larger samples were used, considerably lower vanadium values were obtained as indicated at 31 and 32.

50 Curve 33 for an oil which is considerably lower in vanadium shows the ASTM recommended sample size 34 and the vanadium content of this oil indicated at 35 for the ASTM recommended sample size, which again is about the same as the vanadium value 36 for this oil by the bomb method of the present invention corrected for the blank. Once again when larger samples were run with the ASTM method, lower vanadium values as indicated at 37 and 38 were obtained.

55 An interesting aspect of the invention as illustrated by the drawing is that values which are in each case closely

the same as the values obtained for vanadium using the ASTM recommended sample size, are secured by the present invention using the same sample size throughout. In the technique of the present invention, therefore, unlike the ASTM procedure, it is no longer necessary to vary sample size with vanadium content of the oils under discussion or to make preliminary or pilot runs.

Table 1 shows the comparison of tests made for the same three samples of oil by the ASTM method using substantially the recommended sample weight, and by the bomb method of the invention. In each case sample weight, colorimeter scale reading at 420 m μ , milligrams of vanadium per 50 milliliter, p.p.m. of vanadium and percentage deviation from the average are shown.

It will be evident that if desired the water used to wash out the bomb may be acidified to aid in keeping the vanadium at the valence of 5 until the determination has been completed.

It will be seen that the percentage deviations are of the same order of magnitude when either of these test methods is used.

It will be evident that while the colorimetric determination of vanadium is desirable, other techniques for determining vanadium may be used, such as the flame photometer.

In view of my invention and disclosure, variations and modifications to meet individual whim or particular need will doubtless become evident to others skilled in the art, to obtain all or part of the benefits of my invention without copying the process shown, and I, therefore, claim all such insofar as they fall within the reasonable spirit and scope of my claims.

Having thus described my invention what I claim as new and desire to secure by Letters Patent is:

1. The method of quantitatively determining vanadium in a sample of fuel oil, which comprises placing a sample of fuel oil in a combustion bomb, introducing a modicum of water into the bomb, introducing oxygen under superatmospheric pressure in the bomb, igniting the sample in the bomb and burning the sample thereby converting all of the vanadium to a valence of 5 and dissolving it in the water, cooling the bomb, discharging excess gas from the bomb, washing out the vanadium with water to dilute the solution of vanadium, adding to the solution measured quantities of sulfuric acid, phosphoric acid and sodium tungstate, heating to about boiling temperature, cooling to room temperature, conforming the solution to a quantitative volumetric volume, and determining the vanadium colorimetrically.

2. The method of converting all of the vanadium in a sample of fuel oil to a valence of 5, which comprises placing a sample of fuel oil containing vanadium in a combustion bomb, introducing oxygen under superatmospheric pressure to the bomb, igniting the content of the bomb, burning said fuel oil in the bomb, and determining the vanadium in the content colorimetrically.

3. The method of converting all of the vanadium in a sample of fuel oil to a solution containing all of said vanadium at a valence of 5, which comprises placing said sample of fuel oil containing vanadium in a combustion bomb, introducing a modicum of water to the bomb, introducing oxygen under superatmospheric pressure to the bomb, igniting the content of the bomb, burning the oil in the bomb, rinsing the interior of the bomb with water, collecting the washings, and determining the vanadium in the washings colorimetrically.
